ATTORNEY

UNITED STATES PATENT OFFICE.

HERMAN G. RASMUSSEN, OF IVANHOE, MINNESOTA.

FUNNEL.

1,268,054.

Specification of Letters Patent. Patented May 28, 1918.

Application filed June 29, 1917. Serial No. 177,804.

To all whom it may concern:

Be it known that I, HERMAN G. RASMUSSEN, a citizen of the United States, residing at Ivanhoe, in the county of Lincoln 5 and State of Minnesota, have invented certain new and useful Improvements in Funnels, of which the following is a specification:

This invention relates to funnels, and 10 more particularly to the automatic type in which the liquid ceases to flow automatically when it reaches a predetermined height in the vessel being filled.

The object of the invention is to provide 15 a simply constructed and efficient funnel of this character having improved trigger controlled means operable by the rising of a float for releasing a valve to close the funnel when the liquid within the receptacle 20 rises to a predetermined height.

Another object is to provide simple and 25 efficient means for protecting the valve to prevent the pressure of the liquid flowing through the funnel from accidentally seat-

ing it.

Another object is to provide improved means for insuring the seating of the valve on the release of the trigger.

With the foregoing and other objects in 30 view, which will appear as the description proceeds, the invention resides in the combination and arrangement of parts and in the details of construction hereinafter described and claimed, it being understood 35 that changes in the precise embodiment of the invention herein disclosed may be made within the scope of what is claimed without departing from the spirit of the invention.

40 In the accompanying drawings:

Figure 1 represents a vertical section of a funnel constructed in accordance with this invention and shown applied,

Fig. 2 is a top plan view thereof, and

45 Fig. 3 is a horizontal section taken on the line 3-3 of Fig. 1 looking in the direction of the arrows.

In the embodiment illustrated the funnel comprises the usual inverted cone-shaped body 1 having the ordinary discharge spout 2. A valve seat 3 is arranged at the junction of the spout with the small end of the funnel body as is shown clearly in Fig. 1 and is designed to receive an inverted cone-shaped valve 4 carried by a valve stem 5 which extends longitudinally throughout

the greater portion of the length of the funnel body, this stem being provided at its upper end with an eye 6 whereby it may be grasped and raised when it is desired to 60 open the valve. This valve stem 5 passes through a guide 7 in the form of a sleeve carried by brace arms 8 secured to the inner face of the funnel body, four of which are here shown and which are inclined upwardly and converge toward each other, being preferably integral with the sleeve 7. These brace arms 8 have laterally extending feet 9 which are secured to the funnel body by screws, riveting or otherwise.

70 A hood 10 is carried by a rod 11 supported by the funnel body at a point just above the position of valve 4 and projects laterally on all sides beyond said valve, being designed to prevent the pressure of the 75 inflowing liquid from engaging the valve and seating it before the float controlled means which holds it open has been actuated as will be presently described. The stem 5 of the valve passes loosely through 80 this hood 10 and the hood operates as an additional guide for centering the stem.

The lower end of the stem 5 is provided with a laterally extending catch 12 which is designed to be engaged by a trigger 13 85 shown in the form of a bar fulcrumed intermittently of its ends between apertured ears 14 carried by the inner face of the spout 2, an opening 15 being provided in the wall of said spout through which the bar 13 extends, one end being positioned within the spout and the other end outside thereof, as is shown clearly in Figs. 1 and 3. A rod 16 is pivoted at its upper end to the outer end of the bar 13 and is provided with a float 95 17 preferably constructed of cork although not necessarily so. This trigger when its inner end is engaged with the catch 12 of the valve stem 5 is designed to support the valve in raised position, and on its release, 100 incident to the raising of the float, which is caused by the rising of the liquid within the vessel in connection with which the funnel is used, releases the valve and permits it to drop into closed position on the seat 3. 105

A weight 18 is carried by the valve stem, being here shown positioned thereon between the guide 7 and the hood 10 and which is designed to facilitate the seating of the valve.

110 The lower end of the valve stem 5 is also shown guided and centered by means of cross rods or braces 19, any desired number

of which may be employed, four being here shown.

The trigger 13 with the float 17 depending therefrom is mounted in a chamber 20 formed at one side of spout 2 and which is here shown semi-cylindrical in cross section, although obviously it may be of any other desired configuration. This chamber 20 has an opening 21 in its upper end to 10 permit the air to pass out therethrough so that the gasolene or other liquid which is fed through the funnel 1 into the vessel V may rise in said chamber 20 for actuating the trigger, it being understood that when 15 the liquid rises in said chamber a sufficient distance to elevate float 17, the bar 13 will be tilted on its fulcrum causing the inner end thereof to move downwardly out of engagement with catch 12 and thereby release 20 the valve which is seated by gravity and thus effectively cuts off any further passage of liquid through spout 2.

A support for the funnel 1 is here shown in the form of an annular ring 22 which is 25 designed to rest on a tank or other vessel to be filled by the funnel and is connected with the spout 2 thereof and with the chamber 20 by means of brace arms 23, any desired number of which may be employed, 30 four being here shown. These arms are of a length sufficient to space the ring 22 some distance inwardly from the free end of the spout 2 and chamber 20 as is shown clearly in Fig. 1 so that when said ring rests on the 35 vessel to be filled, the end of the spout may project some distance into said vessel, the flanged opening V' being here shown for the passage of the spout therethrough.

When the device is in operative position 40 the float 17 is preferably so positioned on the rod 16 as to cause it to be disposed a slight distance below the plane occupied by the supporting ring 22 so that it will be spaced about one-quarter of an inch more 45 or less from the top of the vessel V when the funnel is in operative position thereby operating to cut off the entrance of liquid into the vessel after it has been completely filled,

but of course it is to be understood that this float may be adjusted at any desired height 50 on said rod to cut off the supply of liquid to the vessel at the will of the user, it not being necessary that the vessel should be filled to its full extent before this cut off occurs. 55

From the foregoing description, taken in connection with the accompanying drawings, the advantages of the construction and of the method of operation will be readily apparent to those skilled in the art to which 60 the invention appertains and while I have described the principle of operation of the invention together with the device which I now consider to be the best embodiment thereof, I desire to have it understood that 65 the device shown is merely illustrative and that such changes may be made as are within the scope of the claimed invention.

I claim:

A funnel having a valve seat arranged at 70 the junction of the body and spout, centering guides carried by said body and spout, a valve stem mounted to slide in said guides, a valve carried by said stem and adapted to seat on the above referred to valve seat, a 75 lateral projection carried by said stem, a chamber formed at one side of said spout with an opening communicating with the spout, a lever fulcrumed intermediately of its ends in said opening, with one end extending into the path of the projection on said valve stem, a rod pivoted to the other end of said lever and provided with a float, said lever being designed to engage the projection on said valve stem, and hold the 80 valve in raised position whereby the raising of the float incident to the rising of the liquid in said chamber will operate to release the valve. 85

In testimony whereof I affix my signature 90 in presence of two witnesses.

HERMAN G. RASMUSSEN.
